W. Randolph Jr.

UNITED STATES PATENT OFFICE.

CLIFTON M. INGRAM, OF PORTER, OKLAHOMA, ASSIGNOR OF ONE-HALF TO ROBERT DEDMON, OF PORTER, OKLAHOMA.

RAILROAD-CROSSING FLAG SIGNAL.

Application filed April 10, 1924. Serial No. 705,583.

To all whom it may concern:

Be it known that I, CLIFTON M. INGRAM, a citizen of the United States, residing at Porter, in the county of Wagoner and State of Oklahoma, have invented certain new and useful Improvements in Railroad-Crossing Flag Signals; and I do hereby declare the following to be a full, clear, and exact description of the invention, such as will enable others skilled in the art to which it appertains to make and use the same.

This invention relates to a flag or signal for use particularly at railroad crossings in order to apprise the public and traffic of approaching trains both at night and in the daytime, as a safeguard against accidents.

It is aimed to provide a novel and efficient construction wherein the flag will be exposed or in signalling position only while the train is in motion, a construction in which the flag or signal is operated by an electric motor can only descend to a predetermined extent and a construction in which the lighting of one or more lamps carried thereby will be controlled through its movement.

Additional objects and advantages will become apparent from a consideration of the description following taken in connection with the accompanying drawings illustrating an operative embodiment.

In said drawings:—

Figure 1 is a view illustrating the invention diagrammatically in connection with railroad crossings;

Figure 2 is a side elevation showing the improved apparatus;

Figure 3 is a central vertical sectional view through the tower of the apparatus;

Figure 4 is an end view of the tower with the motor housing in section;

Figure 5 is a sectional view taken on the line 5—5 of Figure 3, and

Figure 6 is a diagrammatic view showing the circuit through the lamps of the flag closed.

Like reference characters designate like or similar parts in the different views.

Referring specifically to the drawings and first to Figure 1, a railroad crossing is suggested at A. B designates the tracks over

which the rolling stock travels and the sections of which at the crossing are in a block insulated from the remaining sections of the track as at C. In order to obviate the accidents so frequently occurring at railroad crossings A is the prime purpose of the present invention.

The invention proper has both of its parts arranged in a tower or housing 10 which is supported as by a stand 11 or in any other way at one side of the track adjacent the crossing but so as to be seen by traffic and the public from either side and from a considerable distance.

Normally concealed within the tower 10 intermediate side walls 12 thereof is a flag or signal 13 of any appropriate size and design and color. It is preferred to paint the same red and to equip it with any suitable number of lamps as at 14, which are also preferably red. The flag 13 is adapted to be moved at desired times for signalling purposes from the full line position of Figure 3 to the dotted line position of the same figure. In the dotted line position, it will be below the side walls 12 and subject to the view of the public and traffic.

The flag or signal 13 is normally held elevated through the medium of the weight 15 carried by a cable or flexible element 16 which is trained over a pulley 17 journaled on a short shaft or axle 18. The cable 16 extends from a bar 19 which is riveted or bolted as at 20 to the flag. This bar 19 is movable intermediate guide plates 21 suitably fastened to the inner surfaces of the walls 12 and they have guide pins or studs 22 bridging them and located in an elongated slot 23 of bar 19. Along one edge, bar 19 is provided with raked teeth 24. Raked teeth 24 are in mesh with idler gear wheel 25 journaled on a short shaft 26 bridging walls 12. The gear wheel or pinion 25 in cooperation with the teeth 24 serves to steady the flag during its movement that will later be apparent.

A rack bar 27 parallel to rack bar 19 is rigidly fastened to the flag or signal 13 as at 28. Rack bar 27 is disposed between plates 29 secured to the inner surfaces of walls 12.

and having guide lugs or pins 30 bridging them and disposed in an elongated slot 31 of said rack bar 27. The teeth of the latter rack bar are designated 32 and mesh with the teeth of a gear wheel or pinion 33.

A shelf 34 is offset from one of the side walls of the tower and covered by a casing or housing 35. Mounted on shelf 34 within the housing 35 is an electric motor 36 whose main or transmission shaft is designated 37 and has the pinion or gear whel 33 keyed thereon so that the gear wheel 33 will drive the rack bar 27 when the motor 36 is energized. It will be noted that the teeth 32 extend but part way of the length of bar 27, to the end that the extent of downward driving movement of the flag 13 through the medium of the pinion 33 is limited.

The electric current for operation of the motor 36 may be supplied for instance from a battery 38 having a conductor 39 connected to one of the rails B and a conductor 40 connected to the motor. Another conductor 41 extends from the motor to the companion rail B. The circuit through the motor is adapted to be closed by rolling stock passing over the rail B in any suitable manner. For instance a train or rolling stock may carry, as shown in Figure 1, a shaft or rod 42 rotatable on a horizontal axis. At each end rod 42 has spring arms 43 fastened to it and to followers 44 slideable along the shaft 42. Spring arms 43 carry contact rings 45. As a result of this construction, the arms 43 function as governors through rotation of shaft 42 in order to move at their centers away from the shaft 42 and to move the conductor rings 45 into engagement with the rails B and thus close the electric circuit. All of the parts of this circuit closing mechanism namely 42, 43, 44 and 45 are of suitable conducting metal. Should the train or rolling stock stop within the block B, the springs 43 would tend to flatten and move to their normal position, thus moving the conductor rings 45 toward each other and opening the electric circuit whereupon the motor 36 will become idle and the weight 15 will elevate the flag. However upon the train starting again, the rings 45 will be immediately thrown into circuit closing relation with the rails B.

The lamps 14 are preferably of the electric type and adapted to be illuminated from the same battery 38 as operates the motor. To this end conductors 46 and 47 are connected to the conductors 41 and 40 and lead to contacts 48 and 49 of a circuit closer. Conductor 46 has considerable slack as at 50 to compensate for the movement of flag 13 and such conductor is in series with the lamps 14. Contact 48 is carried by and insulated from the bar 27 while the contact 49 is carried by and insulated from the frame 10 within the housing or tower. Con-

tact 49 is vertically slideable and urged upwardly by an expansive spring 50 engaging the same and a bracket 51 which mounts it. The spring 50 cushions the engagement of the contacts 48 and 49.

It will be understood that all of the wheels on one side of each car are insulated from the axles.

In operation when a train or rolling stock enters the block, the circuit through the electric motor 36 is closed due to the engagement of conductor rings 45 with the rails B. Motor 36 being thus operated drives its shaft 37 and pinion 33 so that the latter will move the flag 13 downwardly into the exposed dotted line position of Figure 3 where it constitutes a signal and a warning to approaching traffic and the public. The flag 13 can only move downwardly to a limited extent since the teeth 32 do not extend the full length of the bar and their length governs the extent of movement of said flag. When the flag approaches its downward limit or signal position, the contacts 48 and 49 engage and thus an electric circuit is closed through the lamps 14 to add to the efficiency of the signal particularly in the night-time. The flag 13 cannot elevate to its normal concealed position while the motor is in operation but when the train passes out of the block, the motor becomes deenergized and idle and hence the weight 15 is free to elevate the flag to normal position. Even should the train stop while in the block, the signal 13 would not be in its signal position since the rings 45 would be retracted due to idleness of shaft 42, and the weight 15 would thus be free to elevate the signal. The flag would however immediately be moved to signalling position upon the train again starting.

Various changes may be resorted to provided they fall within the spirit and scope of the invention.

I claim as my invention:

1. A signalling apparatus of the class described consisting of a signal member, bars extending therefrom, means associated with one of said bars to normally maintain the signal retracted, and means in driving relation with the other bar to project the signal, said bars having elongated slots, guide plates between which the bars are disposed, and means disposed in said slots and coacting with the guide plates to guide the bars, illuminating means carried by the signal, a contact carried by one of the bars in combination with a contact carried by a support and engageable with the first mentioned contact to close an electric circuit through the illuminating means.

2. A signalling apparatus of the class described having a housing consisting of spaced sides, a signal member normally concealed between said sides, parallel bars extending from said signal member, guide

plates secured to said sides, said bars having in mesh with said racked teeth, and an electric motor to drive said pinion. In testimony whereof I affix my signature 10
elongated slots, guide elements cooperating with said slots and said guide bars, a pulley carried by one of the plates, a flexible element extending from one of the bars and trained over the pulley, a weight on said flexible element to urge retraction of the signal, the other bar having racked teeth extending part way along the same, a pinion
